United States Patent Office.

JAMES DAYKIN, OF CLEVELAND, OHIO.

Letters Patent No. 65,353, dated June 4, 1867.

IMPROVEMENT IN WATER-DRAWERS.

The Schedule referred to in these Letters Patent and making part of the same.

TO ALL WHOM IT MAY CONCERN:

Be it known that I, JAMES DAYKIN, of Cleveland, in the county of Cuyahoga, and State of Ohio, have invented certain new and useful Improvements in Water-Drawers; and I do hereby declare that the following is a full and complete description of the same, reference being had to the accompanying drawings, making a part of this specification, in which—

Figure 1 is a perspective view of the drawer.

Figure 2, a top view with the cover detached.

Figure 3, a vertical section.

Like letters of reference refer to like parts in the several parts and views presented.

A, fig. 1, is the case or curb, across the top of which is hung the wheel B, on the shaft C, having its bearings in the side of the curb. D, fig. 3, is a bucket, suspended to the chain or rope E, and counterbalanced by the weight F. This chain is of the ordinary kind, whereas the chain formerly used in this drawer was a flat one, especially made for this purpose with great expense and with less durability. In the bottom of the bucket is a valve, G, to which is connected the rod H, and by which it is operated in a manner as hereafter shown.

The practical operation of this drawer is as follows: The bucket on being drawn up by the crank K, &c., is then discharged of its contents by the rod H (which, it will be seen, projects above the rim of the bucket) striking against the head-board I, which depresses the rod, and thereby opens the valve G. At the same time the inner side of the rim of the bucket strikes against the tilting-board L, the position of which, being slanting in the direction as shown in fig. 3, throws the bottom of the bucket forward over the receiver M, into which the water is discharged through the bottom of the bucket; from thence, through the spout N, to the outside of the curb. The position of the bucket when thus tilted and discharging through the open valve is indicated by the dotted lines *a* in fig. 3, and in which figure it will be seen that the head-board I referred to is thrown upward in line with the top of the bucket, and thereby allows the end of the rod H to be acted upon to the full opening of the valve, which would not be the case if the head-board were rigidly horizontal, as the end of the rod does not strike until the bucket is tilted, the distance being too great between the rim of the bucket and the tilting-board. Thus it will be seen that the head-board adapts itself to the conditions of the bucket, as it is deflected by the tilting-board L, and therefore allows the rod to open the valve to its full extent. The head-board I, being weighted, causes it to return to its horizontal position as the bucket descends. The said board is secured to the shaft J, and is pivoted or hung at each end to the sides of the curb, or otherwise so hinged as to admit of its adjusting itself to the tilting of the bucket. By means of the tilting-board L the bucket, when drawn up to discharge its water, is first tilted to the position noted by the dotted lines *a*, fig. 3; and when it is up in this position the rod H is brought in contact with head-board I, causing the valve G to open to discharge the water. The bucket is at all times first so tilted that the bottom will be over the receiver M before the rod H is acted upon by the head-board I in opening the valve. It matters not in which way the bucket may turn in rising, as the rod H will always be brought at some point under the head-board I, which readily adjusts itself to the top of the tipped bucket, so as to bring the rod H in contact with it; and as this board or plate I is hinged or pivoted it does not open the valve until after the bucket is tilted by the board L, as shown.

As before said, by this arrangement of the head-board an ordinary chain or rope is used, as it can make no difference on which part of the board the end of the rod may strike; hence the flat chain referred to is dispensed with, and that with increased advantage, as the apparatus can be manufactured at less expense by using the ordinary chain than by the use of the flat one especially made for the purpose. It also acts with greater certainty and regularity, and is much stronger and more durable.

What I claim as my improvement, and desire to secure by Letters Patent, is—

1. The pivoted head-board I, arranged in relation to the valve of the bucket substantially as and for the purpose specified.
2. The adjustable head-board or plate I, and tilting-board L, in combination with a chain or rope, E, valve-rod H, and bucket D, when arranged and operating in relation to each other, substantially as and for the purpose set forth.

JAMES DAYKIN.
